UNITED STATES PATENT OFFICE.

THOMAS WEBSTER, OF NEW YORK, N. Y.

APPARATUS FOR BACKING ELECTROTYPESES.

1,193,324.

Specification of Letters Patent.

Patented Aug. 1, 1916.

Application filed June 24, 1915. Serial No. 36,148.

To all whom it may concern:

Be it known that I, THOMAS WEBSTER, a citizen of the United States, and a resident of New York, in the borough of Brooklyn, county of Kings, and State of New York, have invented certain new and useful Improvements in Apparatus for Backing Electrotype, of which the following is a specification.

10 This invention relates to apparatus for backing electrotype, and more particularly has for its object to provide an improved method and apparatus for carrying out this step in the art of electrotyping.

15 Heretofore, when the electrotype was removed from the electrolytic bath, and after it was cleaned of its adhering graphite, it was placed on a backing pan, which had a very smooth surface, and which was cooled 20 by means of an air blower. This electrotype or shell, after it was removed from the wax mold, was thoroughly rinsed with hot water to remove all pieces of wax and foreign substances, and then placed printing face down 25 in the backing pan. An ordinary soldering solution was then applied, and tin foil spread evenly over the back. The pan was then placed on the melting pot until the tin foil became fused. The pan was then swung 30 over to the backing up stand, and the liquid backing metal poured over the shell to the required depth, whereupon the shell with its back was then ready for the cooling process. In order to facilitate the cooling, instead of 35 waiting for the natural air currents to bring about this cooling, a fan or blast blower was provided, whereby the cooling could be completed by means of the blower attachment in about five minutes, whereas with the natural 40 cooling it would take from twenty-five minutes to a half hour. Thus, a great saving of time was gained, that without this assistance could not be obtained. A further reason why a blower attachment was desirable over 45 the natural method of cooling, was on account of its being quicker than the natural method, but in both methods the metal shrinks away from the pan, thus causing irregularities on the printing surface of the 50 plate, which the finisher must necessarily correct before the plate can be delivered in a condition acceptable to the buyer. However, this blast blower cooling did not accomplish all the advantages claimed for it, 55 and my invention consists in providing a distinct improvement over the old blast blower

method of cooling, which consists in bringing the pan with the shell therein, and the backing on the shell and in the pan, against a sheet of heat absorbing material, as felt 60 saturated with water, maintained in communication with continuous supplies of water to make up the loss occasioned by the evaporation when the hot pan strikes the wet felt. Instead of bringing the pan to the felt, the 65 equivalent step of bringing the felt to the pan may be used. The application of the saturated felt pad effects an even distribution of cooling material to the bottom of the pan containing the molten metal and the 70 evaporation of the water intensifies the cooling operation and causes a sudden and even chilling of the surface of the backing in contact with the pan and an increased tendency of the metal to shrink toward the pan where- 75 by irregularities in the face of the shell are avoided.

To carry out my improved process most efficiently, it is advantageous and essential that the pan itself be as smooth as possible, 80 so that the face of the shell will not encounter any obstructions or unevenness in the pan. When the pan is smooth throughout, the weight of the backing, pressing down against the shell, will smooth out any 85 irregularities in the shell itself, and cause the printing surface of the shell to be even throughout, and thereby present to the paper to be printed an entirely even surface without any deepened portions or valleys 90 therein, which cause an uneven effect in the ultimate printing. The printing surface of the shell, thus having been smoothed out or straightened by the operation of the weight of the backing on the shell, does not require 95 any subsequent treatment, as is the case in many of the present shells, which require hammering or planing, or other smoothing out operations.

In the accompanying drawings, Figure 1 100 is a side view with parts in section of the cooling apparatus, and with the pan above it, showing the shell backed by the backing; Fig. 2 is a similar view combined, however, with the apparatus for moving the cooling 105 device up toward the pan, and Fig. 3 is a similar view, showing, however, the movement of the pan toward the cooling apparatus. Fig. 4 represents a vertical section of the apparatus, the absorbent pad being 110 omitted and the cooling pan being in operative position holding the evaporative liquid No.

in contact with the bottom of the backing pan.

Similar reference numerals indicate corresponding parts throughout the several figures of the drawing.

Referring to the drawing, and more particularly to Fig. 1, the backing pan 10 has its upper smooth surface 11 polished off in the well known manner. With the printing face downward and toward this surface 11, a shell 12 is placed, on which shell 12 a layer of alloy backing 13 rests and serves to weight down the shell 12. This is well known and operates in the manner heretofore known. Below the pan 10, a second pan or basin 15 is provided, which has lateral flanges 16 of a height larger than the height of the pan 10. These flanges 16 have an inlet water flow 17, and an outlet water flow 18, each suitably regulated by valves 19 and 20. Within the basin 15, a sheet of felt material 21 is preferably arranged, which is maintained in moist condition by the inlet and the outlet flow of the water through the pipes 17 and 18. The quantity of water is such that the felt is thoroughly saturated with the water, but does not form a layer of water above the surface of the sheet of felt, under normal conditions. When, however, the hot pan 10, with its shell 12 and backing 13, is brought in contact with the sheet of felt, the supply of water must be such as to make up for the evaporation resulting from the hot surface of the pan 10 coming in contact with the moist sheet of felt.

Referring to Fig. 2, the pan 10 is shown as supported by the arms 25 to suitable supporting members 26, and held in stationary position thereby. The basin 15 rests on arms 30 pivoted at 31, and having downwardly projecting arms 32. To the free ends of the arms 32, a rod 34 is pivoted at 33 and its free end again is pivoted at 35 to a lever 36. This lever is supported on a shaft 37 in bearings 38 suitably secured to a table 39, and the shaft 37 is keyed to a handle 40. The lever 36 has its other end pivoted to a rod 41 which is like the rod 34, and this rod 41 is in turn pivoted to the elbow lever 42 at 43, which elbow-lever 42 is like the elbow-lever 32, and is pivoted to the stationary member 45 at 44, and has its hook-shaped end 47 engaging the lower end of the flange 16, in the same manner as the member 30 engages the flange 16 at the other side. Thus it is clear that by the operation of the handle 40, and the movement of the shaft 37, the lever 36 will be operated, and the basin 15, with the felt therein, raised toward the pan. To enable this raising, the pipes 17 and 18 are made flexible.

Instead of raising the basin 15 toward the pan 10, as just described, it may be desirable to lower and raise the pan 10. For

this purpose, a similar mechanism is used as that just described in connection with Fig. 2, but instead of having the elbow lever engage the lower end of the flange 15 of the basin, the arms 30^a and 47^a are connected with links 50 and 51 to the pan 10. The pan 10, supported by the links 50 and 51, carries the shell 12 in contact with its smooth surface and the backing 13 mounting said shell. Thus in the embodiment shown in Fig. 2, by the operation of the handle 40, the basin 15 with its felt pad may be lifted toward the pan 10 until its moist felt pad comes in contact with the bottom of said pan to effect the cooling operation and after such operation the basin 15 may be lowered by an opposite movement of said lever whereby the cooling pad is withdrawn from the pan; whereas in the embodiment shown in Fig. 3 a movement of the lever 40 lowers the pan into contact with the felt cooling pad in the basin and lifts it out of contact therewith. In either case, the principle of my invention consists in bringing the electrotyping pan, with its shell and backing, against the absorbent material for the purpose of cooling the pan. The result of the coöperation and interchanges of heat, is that the material forming the backing 13 in the pan 10, shrinks toward the face of the cast as it cools, and in a very rapid manner, and at the same time the rapid interchange of heat actions brings about a downward pull of the backing against the shell, and serves to weight down the shell and straighten it out against the polished surface 11 of the pan 10. The action is a very quick one in that the heat units of the pan are rapidly absorbed by the felt layer maintained under continued moisture, and thereby the cooling of the backing pans may be readily and quickly brought about with very advantageous and efficient results. This cooling is very much quicker than the cold blast cooling herein described, and in consequence thereof, a very much larger capacity of the plant is obtained, while at the same time the efficiency of the product is markedly increased.

Among the advantages of water cooling are that the plates are all shrunk alike, and the face is drawn down flat, doing away with straightening in many cases, especially on type and half-tones, providing the backing pans are left smooth and clean. Another advantage is that the casts are cooled off in forty seconds, doing away with a five horsepower blower, as is used at present in most establishments.

The pad may be omitted if desired as shown in Fig. 4. In that case the wafer or other evaporative liquid supplied to the cooling box comes bodily into contact with the bottom of the backing pan containing the shell and backing metal to be cooled; 120

but I find it preferable in practice to bring the evaporative liquid into contact with the bottom of the backing pan through the capillary action of the pad. The better effect resulting from the use of the pad is probably due to the fact that the pad distributes the evaporative liquid to the bottom of the backing pan through capillary action and permits the passage of air between the fibers of the pad and increases the evaporation of the liquid and thereby intensifies the cooling effect. The latter is preferable, as stated. However, both ways work efficiently.

15 I have described my invention, but I do not want to be limited to the special way in which the mechanism is shown, as changes may be made therein without departing from the spirit of the invention, as described 20 in the appended claims.

Having thus described my invention, I claim as new and desire to secure by Letters Patent:

1. An apparatus of the character described comprising a backing pan for containing the backed electrotype, a cooling pan for containing a cooling material, and means for moving one of said pans toward and from the other to bring the bottom of 30 the backing pan into contact with and away from cooling material in the cooling pan.

2. An apparatus of the character described comprising a backing pan for containing the backed electrotype, a cooling 35 pan, means for supplying a cooling liquid to said cooling pan, and means for moving one of said pans toward and from the other to bring the bottom of the backing pan into contact with and away from cooling material in the cooling pan.

3. An apparatus of the character described comprising a backing pan for containing the backed electrotype, a liquid absorbent cooling pad, and means for effecting 45 contact and separation between said pad and the bottom of said pan.

4. An apparatus of the character described comprising a backing pan for containing the backed electrotype, an absorbent 50 pad of felt saturated with a cooling liquid, and means for effecting contact and separation between said pad and the bottom of said pan.

5. An apparatus of the character described comprising a backing pan for con-

taining the backed electrotype, an absorbent pad of felt saturated with a cooling liquid, means for effecting contact and separation between said pad and the bottom of said pan, and means for supplying a cooling liquid to the pad during said contact.

6. An apparatus of the character described comprising a backing pan for containing the backed electrotype, a cooling pan, an absorbent cooling pad disposed in 65 said pan and containing a cooling liquid, and means for moving one of said pans toward and from the other to bring the bottom of said backing pan into and out of contact with said cooling pad.

7. An apparatus of the character described comprising a backing pan, means for suspending said pan, a cooling pan containing cooling material and disposed below said suspended backing pan, pivoted 75 levers engaging said cooling pan, and an actuating mechanism for operating said levers to raise and lower said cooling pan into contact with and away from the bottom of said backing pan.

8. An apparatus of the character described comprising a backing pan, means for suspending said pan, a cooling pan containing cooling material and disposed below said suspended backing pan, pivoted levers engaging said cooling pan, a rock shaft disposed between said engaging levers and provided with radial arms, links connecting said arms with said engaging levers, and a handle lever for operating said rock shaft and 85 engaging levers to raise or lower said cooling pan into contact with or away from the bottom of said backing pan.

9. An apparatus of the character described comprising a backing pan for containing the backed electrotype, a cooling pan, means for supplying a cooling liquid to said cooling pan and for withdrawing said liquid from said pan, and means for moving one of said pans toward and from the other 100 to bring the bottom of the backing pan into contact with and away from cooling material in the cooling pan.

In testimony that I claim the foregoing as my invention, I have signed my name in 105 presence of two subscribing witnesses.

THOMAS WEBSTER.
